199,376

BELLOWS FOR FIRING A CHARCOAL BURNER
OR THE LIKE*Robert Lawrence Uttermohlen, 417 W. 4th St.,
Oil City, Pa.*Filed May 10, 1962, Ser. No. 70,069*Term of patent 14 years*(Cl. D62—2)

FIG. 1.

FIG. 3

FIG. 2

FIGURE 1 is a perspective view of a bellows for firing a charcoal burner or the like showing my new design;

FIGURE 2 is a perspective view of a modified form thereof;

FIGURE 3 is a sectional view of a portion of the side of the bellows shown in FIG. 1 taken on a central plane thereof.

The end of the bellows not shown is substantially the same as that shown in FIGS. 1 and 2 except for the omission of the cylindrical nozzle.

I claim:

The ornamental design for a bellows for firing a charcoal burner or the like, as shown and described.

References Cited by the Examiner

UNITED STATES PATENTS

D. 194,715	2/63	Michael	-----	D58—26
1,485,233	2/24	Mallory	-----	137—796
2,397,257	3/46	Goland et al.	-----	128—278
2,686,006	8/54	Hasselquist	-----	230—160

OTHER REFERENCES

Aerosol Age, July 1960, page 21, lefthand corner, aerosol can.

Modern Packaging, April 1958, page 124, left center of page, item No. 2, polyethylene tube with bellows.

WALLACE R. BURKE, Acting Primary Examiner.

ADELINE B. HANNAH, Examiner.